UNITED STATES PATENT OFFICE.

BLOOMFIELD H. HOWARD, OF WASHINGTON, DISTRICT OF COLUMBIA, AND ERNEST J. TURNER, OF PITTSBURGH, PENNSYLVANIA.

CASTING FOR FEEDERS FOR INGOT MOLDS.

Application filed February 15, 1924. Serial No. 693,098.

To all whom it may concern:

Be it known that BLOOMFIELD H. HOWARD and ERNEST J. TURNER, citizens of the United States, residing, respectively, at Washington, District of Columbia, and Pittsburgh, in the county of Allegheny and State of Pennsylvania, have invented certain new and useful Improvements in Castings for Feeders for Ingot Molds, of which the following is a specification.

Our invention relates to improvements in castings for feeders for ingot molds.

The object of our invention is to provide a casting for forming ingot mold feeders made of plastic material for forcing the plastic material under pressure through a passage in the casting whereby a feeder is made of a shape to correspond to that shown in an application of even date.

Another object of our invention is to provide a casting in which a feeder can be formed having a large number of inwardly bellied walls and outwardly curved walls adapted to form ribs on the outer face of the feeder for supporting the feeder on the mold and having a series of inner walls of a contour approximately that of the outer walls.

A further object of our invention is to provide a specially shaped casting adapted to form a correspondingly shaped feeder and having certain arrangement of parts hereinafter more fully described.

In the accompanying drawings:—

Figure 1 is a vertical sectional view of the lower end of a cylinder showing our improved casting attached thereto.

Figure 2 is a transverse sectional view taken on the line 2—2 of Figure 1.

Figure 3 is a view similar to Figure 2 showing the inner portion of the casting of a modified form.

Figure 4 is a view similar to Figure 2 showing a modified form of outer and inner members of the casting.

Referring now to the drawings 1 represents the cylinder the lower end of which is provided with a flange 2 which is attached by means of bolts 3 to the flange 4 of the outer member 5 of the casting. This outer member 5 of the casting is provided with four oppositely arranged inwardly bellied walls 6, 7, 8 and 9. The ends of the inwardly bellied walls 7 and 9 are connected by the outwardly curved walls 10 and 11.

Connecting the outwardly curved walls 10 and 11 with the walls 6 and 8 are the two inwardly curved walls 12 and 13.

The cylinder 1 is provided at the center with a cylindrical member 14 to which is bolted the inner member 15 of the casting by means of a bolt 16. This inner member 15 is provided with four oppositely arranged inwardly bellied walls 17, 18, 19 and 20, which are connected at the corners by the inwardly curved walls 21 and 22.

In Figure 3 of the drawings the outer member 5 of the casting is constructed like that shown in Figure 2 and like reference numerals indicate like parts. In this form the inner member 23 instead of having the walls curved, is provided with four oppositely arranged straight walls 24, 25, 26 and 27 which are connected at each corner by two curved walls 28 and 29.

In Figure 4 the outer member 28 is provided with four inwardly bellied walls 29, 30, 31 and 32 which are connected at the corners by the four straight walls 33, 34, 35 and 36. Each of the inwardly bellied walls 29, 30, 31 and 32 is provided with an outwardly curved wall 37 arranged mid-way its length. The inner member 38 is provided with four inwardly bellied walls 39, 40, 41 and 42 which corresponds to the walls 29, 30, 31 and 32 of the outer member. These walls 39, 40, 41 and 42 are connected at the corners by the four oppositely arranged walls 43, 44, 45 and 46.

In each of the forms, the upper ends of the walls as shown in Figure 1 are beveled as indicated at 47 and 48 which provides a passage having a flared upper end which allows a free passage of the plastic material through the opening, this material being compressed at the lower end.

Having thus fully described our invention what we claim is:—

1. A casting for feeders for ingot molds comprising an outer member having inwardly bellied walls and an inner member having correspondingly shaped inwardly bellied walls.

2. A casting for feeders for ingot molds comprising an outer member having four oppositely arranged, inwardly bellied walls connected at their corners by two inwardly curved walls and an inner member having correspondingly shaped walls.

3. A casting for feeders for ingot molds

comprising an outer member having four oppositely arranged, inwardly bellied walls connected at the corners by two inwardly curved walls and an outwardly curved wall 5 and an inner member having inwardly bellied and inwardly curved walls to correspond to the walls of the outer member.

4. A casting for feeders for ingot molds comprising inwardly bellied walls connected 10 by inwardly curved walls and an inner member having straight walls opposite the bellied walls of the outer member and connected by inwardly curved walls opposite the inwardly curved walls of the outer 15 member.

5. A casting for feeders for ingot molds comprising an outer member having four oppositely arranged inwardly bellied walls having outwardly curved walls intermediate their ends, said inwardly bellied walls connected at the corners by straight walls and an inner member having four inwardly bellied walls corresponding to those of the outer member and connected at the corners by the straight walls. 20

25 In testimony whereof we affix our signatures.

BLOOMFIELD H. HOWARD.
ERNEST J. TURNER.
